DESIGN FOR A CHALK MARKER

Max Ingwer, New York, N. Y., assignor to Consolidated Sewing Machine & Supply Co., Inc., New York, N. Y., a corporation of New York

Application December 29, 1944, Serial No. 117,154

Term of patent 14 years

(Cl. D74—24)

To all whom it may concern:

Be it known that I, Max Ingwer, a citizen of the United States, residing at New York, in the county and State of New York, have invented a new, original, and ornamental Design for a Chalk Marker, of which the following is a specification, reference being had to the accompanying drawing forming part thereof.

Fig. 1 is a side view of a chalk marker embodying my new design;

Fig. 2 is a top plan and Fig. 3 a bottom plan view of the same.

Fig. 4 is an illustration of the device as viewed from the right of Fig. 2.

I claim:

The ornamental design for a chalk marker, substantially as shown.

MAX INGWER.
